UNITED STATES PATENT OFFICE.

JOHN LOYCANO, OF BOSTON, MASSACHUSETTS.

DRAWING-BOARD ATTACHMENT.

Application filed June 25, 1925. Serial No. 39,522.

My present invention relates to drawing board attachments, and more particularly to such attachments for raising and lowering one edge of said table to produce a slanting 5 inclination thereof.

My device is particularly adapted for use on drawing boards of the portable type, wherein the draftsman or person using the same must either do his drawing with the 10 board flat, which results in greater discomfort, or get a slant thereto by placing objects, such as books or the like, under one edge of the board to incline it. So far as I am aware, there are no devices for satisfactorily 15 operating, tilting, inclining, or slanting this type of drawing board.

An important object of my present invention, therefore, is to provide an attachment for drawing boards which may be operated 20 to readily adjust the drawing board to the inclination most desirable to the operator.

A further object of my invention is to provide such a drawing board attachment which will be economical to manufacture, simple to 25 attach and easy to operate, thus satisfying a long felt demand among draftsmen, students of mechanical drawing, and the like.

I so construct my novel attachment that when the person using the same has finished 30 with the board for the time being, my attachment will still be left on the board, but will occupy very little space, and will in no wise be an objectionable addition thereto.

Further features of the invention, novel 35 combinations of parts, and advantages, will be hereinafter more fully pointed out and claimed.

Referring to the drawings illustrating a preferred embodiment of my invention, 40 Fig. 1 is a perspective view illustrating a pair of my attachments in use on a drawing board;

Fig. 2 is a perspective, in enlarged detail, of one of my attachments;

Fig. 3 is a top plan view of a modification; and

Fig. 4 is a side view of the device illustrated in Fig. 3.

As shown in the drawings, 1 designates a 50 table, and 2 a drawing board to which a pair of my attachments are fitted. Since these attachments are identical, description of one will suffice for both.

Fig. 2 illustrates one form of my invention, 55 comprising a body portion 3 provided with flanges 4, 4, the flanges 4, 4 being per-

forated to receive screws 5 for securing the attachment to a drawing board. The body 3 is perforated at right angles to the line of attachment at 6, to receive a rod 7, which 60 rod is slidable through said perforation 6, for adjustability. A set screw 8 is tapped into the body 3 to bind upon the rod and hold it in any adjusted position desired. When the board is no longer desired to be 65 used, the set screw 8 may be loosened, the rod 7 withdrawn, and I have provided a perforation 9, at right angles to the perforation 6, into which the rod 7 may be inserted and again locked in position by the 70 set screw 8. When in this position the rod 7 will be inconspicuous, and out of the way of the operator, and the board may be laid flat or set in any place desired, without injury to the attachment. The set screw 8 75 thus operates to hold the rod in position, regardless of whether the rod is in the perforation 6 or the perforation 9, thus greatly simplifying the device.

Figs. 3 and 4 illustrate a modification, 80 wherein the bracket 10 is secured to the drawing board 2 by screws 11. Pivottally attached to the bracket 10 is a body portion 12, adapted to rotate therein, and having an aperture 13 therethrough to receive the 85 rod 14. On the top of the bracket 10 are provided grooves 15 and 16, in which the rod 14 will rest, a set screw 17 tapped through the swivelled body 12 holding the rod 14 securely in position. An important 90 advantage of this modification is that when the user is temporarily through with the board the set screw 17 will be released, permitting the rod 14 to move out of the groove 15, Fig. 3, and permitting the rod 14 and 95 swivelled body to assume the position shown in dotted lines in Fig. 3, thus placing the rod out of the way of the user. When in this out-of-the-way position, the rod 14 will rest in the groove 16, whereupon the 100 set screw 17 will again be tightened, thus securely holding the same in position. On the bottom ends of both the rods 7 and 14 I provide a tip 18, preferably of rubber or some such resilient and non-slipping material, so that the board 2 will have a firm bearing surface, and the attachment will not injure or mar the desk, table, or the like, 105 on which it is used.

The operation of my present invention 110 will be readily apparent. When it is desired to use the drawing board, with the at-

tachments shown in Figs. 1 and 2, the rod 7 is inserted in the perforation 6, board raised to an inclination to suit the individual requirements of the user, set screw 8 tightened, and board is ready for use. When it is no longer desired to use the board, the set screw 8 is loosened, the rod 7 withdrawn from the perforation 6 and inserted in the perforation 9, whereupon the set screw is again tightened and the rod 7 held in position.

In using the modification shown in Figs. 3 and 4, the set screw 17 would be loosened, the rod 14 turned at right angles to the board, and the board likewise adjusted to the proper inclination, whereupon the set screw 17 would be tightened. When one is through with the board, the set screw 17 should be loosened the rod 14, body 12 should be turned to the position shown in dotted lines in Fig. 3, and the set screw 17 again tightened.

I believe that a drawing board attachment of this kind, being compact in structure, neat in appearance, economical to manufacture, and simple to operate, is new, and I desire to claim both modifications shown herein broadly.

While I have necessarily illustrated my present invention somewhat in detail, it will be appreciated that I may vary the size, shape, and arrangement of parts within reasonably wide limits without departing from the spirit of the invention.

It will also be appreciated that my novel attachments can be used on practically any size drawing board, and any number of the same used thereon. Although for practical purposes a pair of these attachments would be amply sufficient.

It will also be appreciated that my attachments may be utilized in conjunction with other devices than drawing boards, such as frames for making bead work, raffia work, or small hand looms, with equal facility.

My invention is further described and defined in the form of claims as follows:—

1. An attachment for drawing boards and the like, comprising a member adapted to be permanently secured to an edge of the board, and having perforations therethrough, one of said perforations at right angles with the plane of the board, and the other perforation in the plane of the board, a rod adapted

to pass through said first perforation and act as a support for the board, and means to hold said rod in a desired position in said board.

2. An attachment for drawing boards and the like, comprising a member adapted to be permanently secured to an edge of the board, and having perforations therethrough, one of said perforations at right angles with the plane of the board, and the other perforation in the plane of the board, a rod for supporting said board and adapted to pass through said first perforation, means to hold said rod in a desired position in said board, said rod being removed from said first perforation and passed through said second perforation, and held in position by said holding means, when the board is not in use.

3. An attachment for drawing boards and the like, comprising a member adapted to be permanently secured to an edge of the board, and having perforations therethrough, one of said perforations at right angles with the plane of the board, and the other perforation in the plane of the board, a rod for supporting said board and adapted to pass through said first perforation, means to hold said rod in a desired position in said board, said rod being removed from said first perforation and passed through said second perforation, and held in position by said holding means, when the board is not in use, and non-slipping, non-marring means on one end of said rod.

4. An attachment for drawing boards and the like, comprising a member adapted to be permanently secured to an edge of said board, a perforation through said member at right angles to the plane of said board, a second perforation through said member in the plane of said board, a rod for supporting said board and having non-slipping, non-marring means on one end thereof, adapted to be adjustably positioned in said first perforation when the board is in use, and pass through said second perforation when the board is not in use, and means to secure the rod in position in either of said perforations.

In testimony whereof, I have signed my name to this specification.

JOHN LOYCANO.
